(57) **CLAIM**

The ornamental design for a charger carrying case as shown and described.

DESCRIPTION

FIG. 1 is a top rear side perspective view of a charger carrying case according to one exemplary embodiment of the present design.

FIG. 2 is a back view of the charger carrying case of FIG. 1.

FIG. 3 is a front view the charger carrying case of FIG. 1.

FIG. 4 is a left side view of the charger carrying case of FIG. 1.

FIG. 5 is a right side view of the charger carrying case of FIG. 1.

FIG. 6 is a top view of the charger carrying case of FIG. 1.

FIG. 7 is a bottom view of the charger carrying case of FIG. 1.

FIG. 8 is a top front perspective view of a power card associated with the charger carrying case of FIG. 1.

FIG. 9 is a front view of the power card of FIG. 8.

FIG. 10 is a back view of the power card of FIG. 8.

FIG. 11 is a top view of the power card of FIG. 8.

FIG. 12 is a bottom view of the power card of FIG. 8.

FIG. 13 is a right side view of the power card of FIG. 8.

FIG. 14 is a left side view of the power card of FIG. 8.

FIG. 15 is a top rear side perspective view of a charger carrying case according to a second exemplary embodiment of the present design.

FIG. 16 is a back view of the charger carrying case of FIG. 15.

FIG. 17 is a front view of the charger carrying case of FIG. 15.

FIG. 18 is a left side view of the charger carrying case of FIG. 15.

FIG. 19 is a right side view of the charger carrying case of FIG. 15.

FIG. 20 is a top view of the charger carrying case of FIG. 15; and,

(Continued)

FIG. 21 is a bottom view of the charger carrying case of FIG. 15.

The dash-dash broken lines are directed to portions of the charger carrying case that form no part of the claimed design. The dash-dot-dash broken lines are directed to environmental structure of exemplary contents of the charger carrying case and form no part of the claimed design.
